UNITED STATES PATENT OFFICE.

JOHN T. WILKIN, OF CONNERSVILLE, INDIANA, ASSIGNEE TO THE CONNERSVILLE BLOWER COMPANY, OF INDIANAPOLIS, INDIANA, A CORPORATION OF INDIANA.

IMPELLER PUMP OR BLOWER AND DRIVER THEREFOR.

1,189,766.

Specification of Letters Patent.

Patented July 4, 1916.

Application filed August 9, 1915. Serial No. 44,380.

To all whom it may concern:

Be it known that I, JOHN T. WILKIN, a citizen of the United States, residing at Connerville, in the county of Fayette and State 5 of Indiana, have invented a new and useful Impeller Pump or Blower and Driver Therefor, of which the following is a specification.

Rotary blowers or pumps of that type in which there are two parallel shafts carrying 10 mating lobed impellers have their shafts synchronized by mating gears and the shafts are commonly driven by the direct coupling of an engine shaft to one of the shafts. Such an installation necessarily requires the 15 use of heavy synchronizing gears because said gears transmit the driving force to one of the impellers and consequently these heavy gears must have the ends of their shafts supported by a heavy outboard bearing. The crank shaft of the engine must 20 also be supported by an outboard bearing, the coupling between the engine crank shaft and one of the shafts of the blower being arranged between the two outboard bearings. Such an arrangement also involves the 25 provision of considerable floor space, especially where a compound engine is used, and, because of the power transmission through the gears, larger impeller clearances are required, such clearances, of course, reducing the efficiency of the pump or blower.

In such an installation there is a surging of the driving torque from one pump shaft to the other owing to the fact that each impeller offers a variable resistance, this resistance passing through maximum and minimum twice in each shaft rotation and this surging of the driving torque produces back lash in the driving gears.

The object of my present invention is to 40 produce a blower or pump unit of much higher efficiency than can be obtained by the arrangement described above, eliminating the necessity of heavy driving gears, out- 45 board bearings for the shafts of these gears, the outboard bearing of the engine, the coupling between engine and blower shaft, and the engine shaft, the result being obtained by the direct application of the cranks of 50 two engines to the two shafts of the pump or blower.

The accompanying drawings illustrate my invention.

Figure 1 is a side elevation of my improved combination; Fig. 2 an end eleva-

tion; Fig. 3 a diagrammatic section of one form of the blower or pump; and Fig. 4 a diagram showing the load variations.

In the drawings, 10 indicates a blower of the type described comprising the parallel shafts 11 and 12 connected by the synchronizing gears 13 (dotted lines Figs. 1 and 3). These gears are preferably arranged in pairs at each end of the blower structure, as indicated in Fig. 2, and, because there will be 60 comparatively little transmission of driving force through these gears they may be comparatively light and narrow. Connected to the shaft 11 is the crank 16 (dotted lines Figs. 1 and 3) of a reciprocating engine 15, 70 the crank being set in line with the lobe plane of the impeller 17 attached to shaft 11. Connected to the shaft 12, and preferably upon the opposite side of the blower from engine 15, is a crank 19 which is set in line with the lobe plane of the impeller 20 which is carried by shaft 12 and this crank is a part of the engine 21, a companion to engine 15. As indicated in Fig. 2, unit 15 75 may be a high pressure unit and the unit 21 80 a low pressure unit.

By referring to Fig. 3, it will be seen that the maximum resistance is being offered by the impeller 20 in the position indicated, while the minimum resistance is being offered by the impeller 17. The character of these resistances is indicated by the curves B and A, respectively, in Fig. 4, the average effect or resistance of the two being indicated by curve C. With reciprocating power units, connected as described, it will be seen that the maximum driving effect is being exerted upon the impeller carried by shaft 12, in the position indicated in Fig. 3, while the minimum driving effect of the 95 other power unit is being exerted upon the impeller carried by shaft 11 and, as these impellers rotate, there will be a variation of applied force approximating the variation of resistance of each impeller and consequently the transfer of driving torque from one shaft to the other through the synchronizing gears will be a minimum, such transfer being entirely eliminated if the power 100 curve of the motor unit were the same as the 105 resistance curve of the impeller. Practically the two curves do not absolutely correspond, but they so closely approximate that decidedly beneficial results are obtained by the arrangement shown.

Fly wheels 25 will, of course, be provided upon each crank shaft.

From the above it will appear that, because there is no material transfer of driving force from one shaft to the other, the clearances between the lobes of the impellers may be reduced to a minimum and, by having synchronizing gears at each end of the shafts, these gears may be set against each other so as to eliminate all back lash.

I claim as my invention:

1. The combination, with a pump or blower of the lobed impeller type having two impeller shafts, of two reciprocating motor units each having its crank connected to one of said impeller shafts in such manner that each motor will exert its maximum driving effect upon its impeller shaft approximately at the time when the impeller thereof is offering its maximum resistance.
2. The combination with a pump or blower of the lobed impeller type comprising a pair of parallel shafts each carrying a two-lobed impeller and meshing synchronizing gears, of two power units each comprising a crank, each of said power units having its crank attached to one of the impeller-shafts substantially in the lobe plane.
3. The combination, with a pump or blower of the lobed impeller type having two impeller shafts with a two-lobed impeller on each shaft, the impellers on the two shafts intermeshing to produce on each impeller a gradually varying effective radius arm exposed to the fluid action, of two reciprocating motor units each having its crank connected to one of such impeller shafts in such manner that its driving effect on the impeller shaft rises and falls substantially synchronously with the resistance offered by the impeller.
4. The combination, with a pump or blower of the lobed impeller type comprising a pair of parallel impeller shafts each carrying a two-lobed impeller, and inter-

meshing synchronizing gears connecting said two shafts, the impellers on the two shafts intermeshing to produce on each impeller a gradually varying effective radius arm exposed to the fluid action, of two power units, each of said power units having its crank attached to one of the impeller shafts so that the crank arm is substantially on dead center when the lobe plane of the impeller on such impeller shaft coincides with the plane of the two impeller shafts.

5. The combination, with a pump or blower of the lobed impeller type having two impeller shafts with a two-lobed impeller on each shaft, the impellers on the two shafts intermeshing to produce on each impeller a gradually varying effective radius arm exposed to the fluid action, of two reciprocating steam engines each having its crank mounted on one of said impeller shafts in such a manner that when the steam engine is exerting its maximum force on such crank the associated impeller will be offering its maximum resistance.

6. The combination, with a pump or blower of the lobed impeller type comprising a pair of parallel impeller shafts each carrying a two-lobed impeller, and intermeshing synchronizing gears connecting said two shafts, of two reciprocating fluid pressure motor units each having a crank, the cranks of said two units being mounted respectively on two impeller shafts and each crank being substantially perpendicular to the line of reciprocation of its associated motor unit when the lobe plane of the impeller on the impeller shaft carrying that crank is perpendicular to the plane of the axes of the two impeller shafts.

In witness whereof, I have hereunto set my hand at Connersville, Indiana, this sixth day of August, A. D. one thousand nine hundred and fifteen.

JOHN T. WILKIN.
